DESIGN FOR A HUMIDIFIER

Elmer A. Reid, Morrisville, Pa.

Application March 16, 1937, Serial No. 68,202

Term of patent 7 years

To all whom it may concern:

Be it known that I, Elmer A. Reid, a citizen of Great Britain, residing at Morrisville, in the county of Bucks and State of Pennsylvania, have invented a new, original, and ornamental Design for a Humidifier, of which the following is a specification, reference being had to the accompanying drawing, forming part thereof.

The figure is a perspective view of a humidifier showing my design. The other side of the humidifier is substantially like the side shown.

I claim:

The ornamental design for a humidifier substantially as shown and described.

ELMER A. REID.
